CLAIM

The ornamental design for a quantum computer as shown and described.

DESCRIPTION

FIG. 1 is a front right perspective view of the quantum computer showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The claim is directed to the design shown in solid lines and shaded surfaces. Any unshaded surface forms no part of the claimed design. All broken lines in the drawings depict portions of the quantum computer that form no part of the claimed design.
